UNITED STATES PATENT OFFICE.

EDMOND W. T. RICHMOND, OF ROMFORD, ENGLAND.

DESIGN FOR A GAS-STOVE.

SPECIFICATION forming part of Design No. 33,885, dated January 8, 1901.

Application filed December 14, 1900. Serial No. 39,927. Term of patent 7 years.

To all whom it may concern:

Be it known that I, EDMOND WALTER TYRRELL RICHMOND, a subject of the Queen of Great Britain, residing in Summercourt, Romford, in the county of Essex, England, have invented and produced a new and original Design for Gas-Stoves, of which the following is a specification.

The accompanying drawing shows a perspective view of a gas-stove embodying my design.

The leading features of my design are the annular body portion A, the concentric central portion B, the radial wings C, extending from the central portion B across the top of the body portion A, and the laterally-projecting handle D. Around the body portion A is an annular frame E, over the top of which the wings C extend.

The body portion A and the central portion B are ornamented by an annular series of holes and by parallel vertically-arranged grooves. The handle is similarly ornamented, and the annular frame-piece E is ornamented by an annular series of arch-shaped figures arranged close together around the upwardly-inclined periphery of the frame.

I claim—

The design for a gas-stove, substantially as herein shown and described.

In testimony whereof I have hereunto subscribed my name.

EDMOND W. T. RICHMOND.
